US00D918860S

(12) **United States Design Patent** (10) **Patent No.:** **US D918,860 S**
(45) **Date of Patent:** **** May 11, 2021**

(54) **LOW PROFILE SPEAKER**

- (71) Applicant: **Vizio, Inc.**, Irvine, CA (US)
(72) Inventor: **Glen Gihong Kim**, Anaheim, CA (US)
(73) Assignee: **Vizio, Inc.**, Irvine, CA (US)

(**) Term: **15 Years**

(21) Appl. No.: **29/709,116**

(22) Filed: **Oct. 11, 2019**

(51) **LOC (13) Cl.** **14-01**

(52) **U.S. Cl.**

USPC **D14/204**; D14/214

(58) **Field of Classification Search**

USPC D14/204-216, 155-159, 160-173, 187,
D14/188, 203.1-203.8, 217-222

CPC H04R 1/02; H04R 1/021; H04R 1/023;
H04R 5/00; H04R 9/06; H04R 2420/07

(57) **CLAIM**

The ornamental design for a low profile speaker, as shown and described.

DESCRIPTION

FIG. 1 is a perspective view of a low profile speaker showing the new design, shown in its environment of a sound system; FIG. 2 is a perspective view of the low profile speaker of FIG. 1;

FIG. 3 is a top plan view of the low profile speaker of FIG. 1;

FIG. 4 is a front elevational view of the low profile speaker of FIG. 1;

FIG. 5 is a left side elevational view of the low profile speaker of FIG. 1;

FIG. 6 is a rear elevational view of the low profile speaker of FIG. 1;

FIG. 7 is a right side elevational view of the low profile speaker of FIG. 1; and,

FIG. 8 is a bottom plan view of the low profile speaker of FIG. 1.

The dashed lines in FIG. 1 depict environmental structure and form no part of the claimed design. The dashed lines in FIG. 4-8 depict portions of the low profile speaker that form no part of the claimed design.

1 Claim, 5 Drawing Sheets
